UNITED STATES PATENT OFFICE.

CHARLES J. SPILL, OF SPRINGFIELD, MASSACHUSETTS.

SHANK-BUTTON.

1,143,457.

Specification of Letters Patent. Patented June 15, 1915.

Application filed June 24, 1912. Serial No. 705,571.

To all whom it may concern:

Be it known that I, CHARLES J. SPILL, a citizen of the United States, and a resident of Springfield, in the county of Hampden and State of Massachusetts, have invented certain new and useful Improvements in Shank-Buttons, of which the following is a specification.

The present invention relates to buttons, 10 and particularly to buttons provided with shanks.

In the prior art it has been customary to insert a pin through the hole in the button blank and then subsequently to bend the pin 15 into the shape of a shank. This is objectionable because the pin is not held firmly in the button blank, and also because the pin is apt to become unbent when subjected to even a moderately severe strain. It has also 20 been attempted to insert a looped double-ended member through the button blank and then clench the same in position to hold the pin and expanding the loop to form a shank. This is objectionable because the 25 clenching operation cannot be performed if the button blank is of glass, agate, pearl, ivory, vegetable ivory or porcelain—which materials are those most commonly used in the manufacture of buttons. To utilize this 30 method the button blank must be made of compressible material.

The object of the present invention is to overcome these various objections and to produce a shank button in which the shank 35 is held firmly in position and will not become unbent when subjected to strains.

The invention further consists of a shank button comprising a button blank having a hole extending through from the face to the 40 back of the blank, and a looped double-ended pin having means as a head on one end for engaging the face of the button blank, said loop being expanded on the back of the button blank to hold the head against the face 45 of the button blank and to form a button shank on the back.

In connection with the foregoing, one or 50 more wedge-shaped portions are provided on the pin and the hole in the button is made tapered toward the back of the blank. Also the head on one of the free ends of the pin is offset laterally to cover the other free end.

Other features will appear as the specification proceeds.

55 In the accompanying drawings the inven-

tion is illustrated in a concrete and preferred form, but changes may of course be made without departing from the legitimate and intended scope of the invention as expressed in the appended claims.

In the said drawings: Figure 1 is a vertical sectional view through a button blank showing the pin inserted, and also the means for supporting the button blank. Fig. 2 is a view similar to Fig. 1 with the loop expanded. Fig. 3 is a section of the line 3—3 of Fig. 2. Fig. 4 is a top view of Fig. 2.

Similar characters of reference indicate corresponding parts in the several views.

1 indicates a button blank preferably provided with a tapered hole 2, said taper extending toward the back 3 of the blank 1.

4 is a looped double-ended pin, preferably provided with wedge-shaped surfaces 5 and preferably having a head 6 on one of the free ends 7 of the pin 4, offset laterally as shown to cover the other free end 8 of the said pin. The said head 6 is adapted to engage with the face 9 of the button blank.

In practice the button blank 1 is placed on a suitable support 10, the pin 4 is then inserted through the hole in the button blank so that the head 6 engages with the face 9 of the button blank. The loop 11 of the pin is then expanded to form a shank 12 and at the same time acts to draw the free end 8 down through the hole 2 of the button blank, thereby wedging the pin in the said hole, and bringing the head 6 home against the face 9. Suitable means may be employed to hold the head 6 of the pin while the loop is expanded. The button blank is preferably of some incompressible material such as glass, agate, pearl, ivory, vegetable ivory or porcelain, and the pin is preferably of metal or other material capable of being bent.

What is claimed, is:

1. As a new article of manufacture, a shank button comprising a button blank having a hole extending therethrough from the face to the back of said blank, said hole being tapered toward the back of the blank, and a looped double-ended pin provided with a wedge-shaped portion extending through the hole aforesaid to engage with the tapered walls thereof, a laterally extending cap formed on one end for engaging with the face of the button blank, said loop being expanded on the back of the button blank to draw said wedge portion and cap

into engagement with the blank and thereby firmly hold the pin in the hole and to form a shank.

2. As a new article of manufacture, a shank button comprising a button blank having a hole extending through from the face to the back of said blank, and a looped double-ended pin having both ends extending into the hole in the blank, a laterally extending cap formed on one of said ends to engage with the face of the button blank to cover said hole therein, said loop being expanded on the back of the button blank to hold the cap against the face of the button blank and to form a button shank on the back.

3. As a new article of manufacture, a shank button comprising a button blank having a hole extending through from the face to the back of said blank, said hole being tapered toward the back of the blank, and a looped double-ended pin having each of said ends formed with wedge-shaped portions adapted to engage with the tapered walls of the hole aforesaid, and a capping

means on one end for engaging with the face of the button, said loop being expanded on the back of the button blank to hold the pin in the hole and to form a shank.

4. As a new article of manufacture, a shank button comprising a button blank having a hole extending through from the face to the back of said blank, and a looped double-ended pin adapted to extend through said hole, means formed on the ends of said pin to lie within said hole to prevent the same from being drawn through the back of said blank, a cap on one end offset laterally to extend over the free end of the pin and covering said hole, said loop being expanded on the back of the button blank to hold the pin rigidly in the hole and to form a shank.

Signed at Springfield, in the county of Hampden and State of Massachusetts, this tenth day of May A. D. 1912.

CHARLES J. SPILL.
